(57) CLAIM

The ornamental design for a wheel cap for automobile, as shown and described.

DESCRIPTION

FIG. 1 is a front left perspective view of a wheel cap for automobile.

FIG. 2 is a front view thereof.

FIG. 3 is a right side view thereof.

FIG. 4 is a left side view thereof.

FIG. 5 is a top view thereof; and,

FIG. 6 is a bottom view thereof.

The broken lines shown in the drawings illustrate portions of the wheel cap for automobile that form no part of the claimed design.
